ATTORNEY.

UNITED STATES PATENT OFFICE.

ELIZABETH LYNCH, OF MINNEAPOLIS, MINNESOTA.

SCREEN.

1,332,131.

Specification of Letters Patent. Patented Feb. 24, 1920.

Application filed July 15, 1919. Serial No. 310,920.

To all whom it may concern:

Be it known that I, ELIZABETH LYNCH, a citizen of the United States, residing at Minneapolis, in the county of Hennepin and State of Minnesota, have invented new and useful Improvements in Screens, of which the following is a specification.

The object of my present invention is the provision of a window or door screen, designed more particularly as a specific improvement upon the screen constituting the subject of my Letters-Patent No. 1,109,437 of September 1, 1914, and in which the upper end of the screen cloth is connected to the frame without impairing the capacity of the screen in permitting flies to pass out of a room.

To the attainment of the foregoing, the invention consists in the screen construction hereinafter described and definitely claimed.

In the accompanying drawings, hereby made a part hereof:

Figure 1 is an elevation illustrative of the improved side of my improved screen.

Figs. 2, 3 and 4 are detail vertical transverse sections, taken in the planes indicated by the lines 2-2, 3-3 and 4-4, respectively, of Fig. 1.

Fig. 5 is a horizontal transverse section taken in the plane indicated by the line 5-5 of Fig. 1, looking downwardly.

Similar numerals of reference designate corresponding parts in all of the views of the drawings.

The lower cross-bar 1 and the side bars 2 of the screen frame may be and preferably are of the ordinary well known construction, and the same is true of the lower molding strip 3, the side molding strips 4 and the major portion of the screen cloth 5.

In furtherance of my invention the upper cross-bar 6 of the screen frame is provided at points intermediate of its transverse center and its ends with recesses 7, the walls 8 of which are inclined inwardly from the outer side of the frame bar 6 to the lower edge of said frame bar where a substantial edge point 9 is left for an important purpose hereinafter set forth. The provision of the

said recesses 7, located as stated, leaves the upper bar 6 with an intermediate portion 10 and end portions 11 for the connection of a molding strip section 12 and molding strip sections 13, respectively.

Also, in furtherance of my present invention the upper portion of the screen cloth 5 is cut so that end extensions 14 thereof are interposed and secured between the molding strip sections 12 and 13 and the portions 10 and 11 of the upper bar 6. The said cutting of the upper portion of the screen cloth affords screen ledges 15, and these ledges 15 are strongly secured to the lower edge of the upper bar 6, as shown. In the said ledges 15 are provided openings 16 through which flies may pass and thereby escape from the room, that is guarded by my novel screen.

It will be apparent from the foregoing that my improved screen construction may be embodied either in a window screen or in a screen door, in the discretion of the manufacturer; also, that by virtue of the construction specifically set forth, the connection of the upper portion of the screen cloth to the upper bar 6 of the frame is rendered strong and durable without impairing the capacity of the screen in permitting the outward passage of the flies.

Having described my invention, what I claim and desire to secure by Letters-Patent, is:

A screen comprising a frame the upper bar of which is provided at its outer side with intermediate recesses arranged at points between its transverse central portion and its end portions, a screen cloth the upper portion of which is cut and has upward extensions, in the same plane as its major portion, and secured against the outer sides of the said transverse central and end portions of the upper bar and also has between said upward extensions ledges extending inwardly at substantial right angles to its major portion and below the said recesses and secured to the lower edge of the upper bar, and escape openings in said ledges.

In testimony whereof I affix my signature.
ELIZABETH LYNCH.
